UNITED STATES PATENT OFFICE.

MAX J. MARYMONT, OF BROOKLYN, NEW YORK.

COMBINATION BILL AND KEY FOLDER.

Application filed April 15, 1925. Serial No. 23,246.

To all whom it may concern:

Be it known that I, MAX J. MARYMONT, a citizen of the United States, residing at Brooklyn, in the county of Kings and State 5 of New York, have invented certain new and useful Improvements in Combination Bill and Key Folders, of which the following is a specification.

The present invention relates to pocket-books or bill folders and has for its object 10 to provide a pocket-book or bill folder combined with an additional folder for holding keys to form a single article and to thus eliminate the use of separate folders for bills and keys.

Another object of this invention is to construct the additional folder, so that the keys suspended therein can be individually withdrawn or pulled out from the case to facilitate 20 the use thereof.

A third object is to provide means in said folder, whereby the keys, when not used, are securely held in position.

With these and other objects in view, my 25 invention consists in the combination, arrangement and construction of parts as will be hereinafter more fully described and defined in the appended claims.

In the drawing in which similar reference 30 characters denote corresponding parts, Fig. 1 is an elevation of the folder seen from the back of the bill folder with the flaps thereof opened; Fig. 2 is a cross-section on line 2—2 of Fig. 1; Fig. 3 is a longitudinal section on line 3—3 of Fig. 1; Fig. 4 is a partial elevation similar to Fig. 1 of a modified construction; Fig. 5 is a section on line 5—5 of Fig. 4; Fig. 6 is a partial elevation similar to Fig. 1 of another modification; Fig. 7 is a section on line 7—7 of Fig. 6 and Fig. 8 is a section on line 8—8 of Fig. 6.

The article forming the subject of this invention comprises a main folder 10 for bills or the like, which may be of leather and of the usual construction, and an auxiliary or additional folder 11 of the same material stitched or otherwise fixed to the outer face of the back of the main folder 10, as at 11'. 12 denotes the flaps of said folder 11, which, like those of the main folder, are adapted in closed position to overlap one another and be buttoned by snap buttons and eyelets 13, 14 as usual. To the inner face of the folder 11, according to the construction shown in Figs. 1, 2 and 3, is

fixed by eyelets 15' or the like a rigid plate 15 of metal or other suitable material, which may by stamping or otherwise be formed with a plurality of pairs of parallel flanges 60 16' extending transversely of the plate 15. These flanges are recessed longitudinally, as at 16' and the slits of each pair of flanges serve to slidably engage a member, such as a pin 17 or the like, from which a key 65 k may be pivotally suspended as by means of a resilient hook or the like 17'. When not in use, the hooks 17' occupy positions near the inner ends of the slits 16' and the keys lie flat against the inner face of the 70 folder to be concealed by the flaps 12, when in closed position. When it is desired to use one of the keys of the bunch, the flaps are unbuttoned and unfolded and on grasping the desired key k, the latter together 75 with its hook 17' is turned around the axis of its pin 17 and simultaneously pulled outwardly to the extreme outer end of the slit.

The object of making the suspension pins 80 17' slidable is to permit the keys to normally 85 occupy a position within the folder where their heads will be concentrated nearest to the middle part of the folder and will not be too close to the edge of the folder. In this manner, the overlapping heads of the adjacent keys, which become quite bulky, particularly when two or more keys are suspended from a single hook, will not hinder the closing and buttoning of the flaps 12 and the folder in closed position will not be 90 bulging at its edges, but near the middle part thereof. At the same time the clearance desired between the key turned outwardly for use and the folder may be obtained even with a relatively short hook. 95

To simplify the construction, each hook 17' carrying a key may be pivotally mounted in a separate base plate 18, which is longitudinally recessed, as at 18', to slidably engage a rivet or pin 19 projecting from the 100 inner face of the folder 11. This modification is shown in Figs. 4 and 5. The several plates are arranged side by side with their adjacent edges bearing upon one another. The pivotal connection of the hook with its 105 corresponding plate is obtained by a pin bearing in the rolled up or tubular outer edge 18' of the plate.

In the modification shown in Figs. 6 and 7, the individual plates 20 to which the hooks 17' are pivotally secured by the pins 17 bearing in the rolled up edges 20' of the

plates 20 are slidably mounted in grooves 15^b formed in the base plate 15^a and extending transversely thereof. The sides of these grooves 15^b are dovetailed or bevelled to engage the correspondingly shaped edges 15^c of the plates 20, thereby securing rectilinear movement. Pins 21 projecting from the base plate 15^a and extending through longitudinal slots 20' provided in the individual plates 20 serve to limit the movement of the latter. To hold the individual hooks in position, while one of the keys is in use, I may provide on the base plate 15 (Fig. 1) or on the individual plates 20 (Fig. 6) snap members 15² or 22 respectively adapted to engage the shanks of the hooks 17' when in normal position.

Since various other modifications may be made in the construction of the key supporting means without departing from the principle of my invention, I do not wish to restrict myself to the details described and shown.

What I claim is:—

1. A folder for keys comprising rigid means fixed to the inner face of said folder, a plurality of key supporting members carried by said rigid means and means for retaining individually said key supporting members in position, when not in use. 25 30

2. A folder for keys comprising rigid means fixed to the inner face of said folder, a plurality of key supporting members pivotally and slidably carried by said rigid means and means for retaining individually 35 said key supporting members in position, when not in use.

3. A folder for keys comprising a rigid means fixed to the inner face of said folder, a plurality of key supporting members movably carried by said rigid means and means for retaining individually said key supporting members in position, when not in use. 40

In testimony whereof I affix my signature.

MAX J. MARYMONT.
